UNITED STATES PATENT OFFICE

EDDIE F. BENNETT, OF EASTLAND, TEXAS

GROUNDING DEVICE

Application filed March 28, 1929. Serial No. 350,541.

This invention relates to grounding devices for use with electrical apparatus and more particularly to a grounding device for use in conjunction with radio and telephone receiving and sending apparatus.

An important object of the invention is to provide a device which will insure at all times a proper grounding contact.

As is well known to those familiar with the art, an ordinary grounding device even though embedded in the ground is often faulty in its operation for the reason that the ground about the same becomes dry so that it is a less efficient conductor. Accordingly, an important object of the invention is the provision of a structure of this character embodying means for constantly keeping the ground thereabout in a moist condition.

A further object of the invention is to produce in a structure of this character an arrangement such that the moisture is introduced to the ground below the level thereof and accordingly does not cause a muddy place about the grounding implement.

A still further object of the invention is to provide an apparatus of this character which may be very readily installed, which may be cheaply manufactured, and which will be durable and efficient in service.

A still further object of the invention is to provide a device which may be driven into the ground adjacent a buried grounding device and employed to furnish moisture to the grounding device to insure the integrity of its contact.

A further object of this invention is to produce in a structure of this character an arrangement whereby the moisture may be permitted to enter the ground below the surface thereof so that the moisture will not be quickly absorbed, the water outlet in the tube having means by which the seepage of the water from the tube into the ground may be controlled so that a relatively small reservoir may be used so as to keep the device functioning and require filling of the reservoir or container approximately once a week.

These and other objects I attain by the construction shown in the accompanying drawing, wherein for the purpose of illus-

tration is shown a preferred embodiment of my invention and wherein:

Figure 1 is a side elevational view of a grounding device constructed in accordance with an embodiment of my invention; 55

Figure 2 is an enlarged vertical sectional view therethrough;

Figure 3 is a section on the line 3—3 of Figure 1.

Referring now more particularly to the drawing, the numeral 10 generally designates a tube, one end of which is provided with a driving point 11 preferably produced by flattening one end of the tube. The upper end of this tube is open and provides a seat for a disc 12 having a spout 13 which enters the upper end of the tube for a short distance. This disc fits against the lower end of the mouth 14 of an inverted water jar 15 and is held in position thereagainst through a threaded clamping ring 16.

The tube 10 adjacent to but in spaced relation to its bottom has formed therethrough an opening 17 and adjacent its upper end has mounted therein a binding post 18 to which the ground connection of the electrical apparatus may be applied. 75

In the use of the apparatus, the tube 10 is driven into the ground to an extent placing the opening 17 below the level of the ground 80 while maintaining the binding post 18 above the surface thereof. This tube may then be filled with water by pouring water into the upper end thereof after which the inverted water jar, which has been previously filled, is 85 placed therein. Water will seep from the tube through opening 17 and moisten the ground about the tube below and adjacent to this opening. As the water seeps from the tube and the lower end of spout 13 is exposed 90 additional water will enter the tube to replace that passing from the opening. In order to maintain the tube filled with water it is merely necessary that the water jar be replenished from time to time. 95

The tube 10 may be made of any suitable material having good conducting qualities and since the body of water contained therein will be constantly in contact not only with the ground but likewise with the inner end 100

or head 19 of the binding post 18 which is extended through the wall of the tube, a perfect contact to this binding post is obtained.

As the construction employed is obviously capable of a certain range of change and modification without materially departing from the spirit of the invention, I do not limit myself to such specific structure except as hereinafter claimed.

10 I claim:—

15 In combination, a grounding device comprising an elongated tubular member having a flattened lower end and an open upper end, said tube also having an opening in the wall thereof intermediate the ends of the tube, a terminal secured to the tube adjacent the upper end thereof, and a drip member loosely mounted on the upper end of the tubular member, said drip member comprising a 20 reservoir, a cone-shaped drip nozzle depending within the upper end of the tubular member, an enlarged flange secured to the base of said cone-shaped nozzle, said flange normally engaging the upper end of the tubular member, and means for securing said flange to said reservoir.

25 In testimony whereof I hereunto affix my signature.

EDDIE F. BENNETT.
